CONDUCTOR REEL

Isaac Stern and Leah Shookhoff, Brooklyn, N. Y.;
said Shookhoff assignor to said Stern

Application May 12, 1934, Serial No. 725,286

10 Claims. (Cl. 242—107)

The invention relates to reels and more particularly relates to novel apparatus for and methods of reeling extensions of electrical conducting wires, specifically telephone conductors extending from the receiver to a telephone.

Two conductors extend from the base of a telephone; one from the base of the telephone to the switch or outlet box and the other from the base to the microphone and receiver unit. The latter conductor, as is common knowledge to users thereof, constantly tends to curl and twist and accordingly becomes extremely annoying on an office desk. Many devices have been proposed for overcoming this difficulty, such as the use of a spiral shaped wire intended to hold the conductor from curling, but these have never effectively prevented curling of the conductor; in fact, seem to assist in the curling.

The provision of an ordinary reel for reeling the wire on a drum when the telephone receiver is not in use and mounted on its base is not by itself practical, due to the fact that ordinarily some form of collector rings are necessary at the end of the wire for completing the electrical circuit as the wire is rolled on and off the reel. Such an arrangement involves the difficulties of contact trouble which, in the case of the relatively small telephone currents, are sufficiently serious that the telephone companies do not permit the application of such a device to their circuits.

It accordingly becomes necessary to provide an arrangement which will permit the conductor to be reeled without in any way altering the present electrical circuit or requiring any contacting devices.

In accordance with the present invention a simple inexpensive reel is employed which permits the wire to be wound on the reel when the telephone is not in use and removed from the reel when the receiver is in use without involving the use of contacting devices such as rings and the like.

Accordingly an object of the invention is to provide a novel reel.

A further object of the invention is to provide novel apparatus for and methods of reeling a telephone receiver conductor.

Still a further object of the invention is to provide a reel which is spring operated and provided with means for locking the cord in its extended or used position and automatically releasing the lock to wind up the conductor after the telephone is restored to its base.

Still another object of the invention is to provide a novel telephone base for automatically con-

cealing the wire of the telephone while the telephone is not in use.

There are other objects of the invention which together with the foregoing will appear in the detailed description which is to follow in connection with the drawing in which:

Figure 1 is a side elevation of a telephone apparatus showing application of one form of the invention;

Figure 2 is a longitudinal external view taken on line 2—2 of Figure 1;

Figure 3 is a longitudinal sectional view taken on line 3—3 of Figure 1;

Figure 4 is a sectional view taken on line 4—4 of Figure 3;

Figure 5 is a sectional view taken on line 5—5 of Figure 3;

Figure 6 is a sectional view taken on line 6—6 of Figure 3;

Figure 7 is a view taken on line 7—7 of Figure 1;

Figure 8 is a view taken on line 8—8 of Figure 5;

Figure 9 is a view taken on line 9—9 of Figure 6.

Referring to Figure 1, reeling device 30 is shown applied to a telephone apparatus stand 31. In this illustration the reel 30 is mounted on the stem of the telephone base by means of clamp 40 (Figures 1 and 7).

The reel 30 consists of drum 41 (Figure 3) which revolves within the casing formed by cylindrical wall 37 and end covers 38 and 39. Drum 41 is provided with a tubular hub 44, pivoted at its ends, as at 45, where it engages pivot 42 fitting in a hole in end wall 47 of the drum, and as at 46, where an extension of the hub itself fits loosely in bearing 43.

A helical rib 35 is formed upon the drum's cylindrical wall 56 for the purpose of guiding turns of the conductors as it is wound on the drum. At the left end of the drum 41 (Figure 3) plates 47 and 48, both rigidly attached to the drum's hub 44, form a narrow compartment 50 to keep loosely formed loops 64 (Figure 5) of cord in shape.

The end portion 34 of the conductor 64 (Figures 1 and 5), extending from the base of the telephone apparatus, is inserted through opening 51 (Figure 5) where it is held fast against slipping by spring tongue 52 (Figure 8) which grips the conductor's covering. The conductor is then formed into one or more large loose loops 64 within the narrow compartment 50, as shown, and brought tangent to hub 44 and thence inserted to the space on the opposite face of plate 48 through slotted opening 53 (Figure 6) and brought behind clamping tongue 54 and toward the cylindrical wall 56 of drum 41. Tongue 54

clamps the portion of the conductor opposite to prevent relative movement thereof for the reason to be explained hereinafter.

The conductor is then passed through opening 55 in cylindrical wall 37 of drum 41 (Figures 3 and 9) and wound up within adjacent turns of helical rib 35. The conductor is then brought out of casing through slot 57 (Figure 2) which extends throughout the entire length of the cylindrical wall 37 of the casing and finally connected to the telephone receiver 32 (Figure 1).

When end portion 33 of the conductor connected to the receiver is pulled out by lifting receiver 32 from its hook on base 31 and pulled toward the subscriber, the portion of the conductor wrapped around the drum 41 will unwind itself, as the drum rotates on its pivots in the direction of arrows (Figures 4, 5, and 6). As the turns of the cord on the drum are being exhausted, the cord will travel through slot 57 along the length of the slot.

Meanwhile, as the drum rotates and the radial portion of the conductor extending from clamp 54 to the cylinder wall rotates about the hub, that portion of the cord forming the slack loops 64 (Figure 5) extending between the clamp at 52 and tongue clamp at 54 will wind itself upon hub 44 of the drum in the space between plates 47 and 48. Since the drum and its hub are made to differ largely in diameter for a relatively great length of cord wound on the drum there corresponds but a small length of the same cord wound upon the hub.

Thus, for example, for a conductor about 42" long, 35" wound on a drum approximately 3" in diameter will require approximately four turns. If the hub is approximately $\frac{1}{2}$ " in diameter, it will reel approximately $1\frac{1}{2}$ " of the slack conductor for each revolution and in four revolutions, making suitable allowance for changes in diameter as the slack wire is reeled on the hub, approximately 7" of conductor will thus be reeled and the slack taken up.

During the unwinding operation the drum will rotate in the direction of the arrows (Figures 4, 5, and 6) against the torsional resilient resistance of coil spring 65. Spring 65 is placed within tubular hub 44 and anchored at the ends, as at 66 (Figure 3) where bent end of the wire fits in the opening in end plate 47 (which rotates together with the drum) and as at 67, where the bent end of the wire fits in the hole in stationary end cover 38. The coil spring's initial tension will increase as the drum rotates, as the conductor is being withdrawn from the reel, twisting the spring.

When the conductor is released after being withdrawn, the accumulated tension in the spring 65 will force the drum 41 to rotate in a direction opposite to that shown by the arrows, causing the conductor to rewind itself on the drum. During this rewinding operation the helical rib 35 (Figure 3), since its turns are spaced apart just enough to accommodate only one turn of the conductor in the space between each pair of ribs, and since its outward edge comes near the inner surface of cylindrical wall 37, effectively guides the conductor in the spiral grooves formed on the drum without jamming.

It will be noted that with this method of reeling, no break in the conductor by contacting slip rings or the like is needed. Without in any way disturbing the telephone conductor, it may be placed in the reel, and as the reel rotates to withdraw wire, the slack conductor is reeled on

the hub or smaller drum. As the conductor is reeled in place on the drum, the reeled conductor on the hub again forms a slack. Thus contacting rings, breaks, etc., which have rendered effects to reel these conductors impractical, if not inoperative, heretofore, are avoided.

Moreover, as an examination of the several views will reveal, the conductor may be installed without any cuttings or disconnections from telephone base or receiver. In fact, the cord is placed upon the drum, as described, with casing 37 and end walls 38 and 39 removed. Slotted opening 57 of casing 37 is open at both ends so that the casing may be put in position after slipping the cord through the slotted opening. The cylindrical casing 37 is provided with an opening 51 (Figures 5 and 8) and a slot 59 in the casing (shown in dotted line in Figure 8), leads to this opening so that the cord may be inserted in the opening by slipping it through the slot. When covers 38 and 39 are placed on the end of the cylindrical casing 37, the flanges of the covers close the slots 57 and 59 and retain the cable in the opening.

Covers 38 and 39 are secured to the ends of casing 37 by means of screws 60 and 61 which go through holes provided in covers and are screwed into threaded holes in lugs 63 (Figure 4) of the casing.

The reeling device so far described may be provided with some means for locking the drum when the desired length of conductor has been withdrawn, so as to relieve the hand of the user from the task of holding the drawn-out portion of the conductor tight against the force of the spring. This means may in particular consist of the ratchet mechanism shown in Figure 4.

In Figure 4, the bearing 43 for hub 44 (Figure 3) has teeth 68 in the form of a ratchet. Two (as shown) or more pawls 69 and 70 are carried by rotating wall 73 of the drum, and are free to swing on pivots 71 attached to that wall. These pawls are apt to engage ratchet teeth 68 which are so shaped that the pawls may ride over them without obstruction when the drum rotates in the direction of the arrows; that is, during the unwinding operation. But when the drum is made to rotate slowly in a direction opposite to that shown by the arrows, the pawl that happens to be directly above the ratchet teeth will fall by gravity and engage and lock with the teeth, preventing the drum from being driven by its spring 65 to rewind the conductor. This will, therefore, lock the drum against rotation opposite to that of the arrows.

If, on the other hand, the conductor is suddenly jerked and released, the drum will first rotate rapidly in the direction of the arrows. The pawl 69 engaged to the ratchet teeth will spread out of disengagement from the teeth due to the centrifugal force developed. When now, immediately following the jerk of the conductor, it is released, the drum will rotate fast in the opposite direction and the pawls, already spread out of disengagement, will be maintained so by virtue of the centrifugal force developed, before having time to fall into engagement with the ratchet teeth.

The tension of coil spring 65 may be adjusted by removing screws 61 (Figure 3) and turning cover 38 so as to twist (or untwist) the spring to the desired tension.

When receiver 32 (Figure 1) is placed on the telephone stand in idle position, the tension of conductor portion 33 is undesirable. Further-

more, the drum, having taken in all the available conductor connected to the receiver, might not have been locked by ratchet mechanism, since such mechanism works to a certain extent on the basis of probabilities, causing, thus, the undesirable tension on the conductor. To avoid this, stop 36, which is made large enough not to go through slot 57, is rigidly fastened to the conductor at a convenient distance from the receiver.

10 Although, in this modification, the loop 64 is shown as wound in the chamber formed by plates 47 and 48, it will be obvious that this loop can be wound along the hub in the space between the hub and the inside wall of the cylinder.

15 Moreover, although normally the conductor 64 is slack or in a loop when the conductor is wound on the reel, the reverse may be obtained by normally arranging the conductor 64 so that it is wound on the hub, while the main portion of the 20 conductor is on the reel and while the reel is being turned to unwind the conductor therefrom, the loop 64 is formed.

The latter method has the advantage that it calls for less work by the spring 65 while the 25 conductor is being unreeled. In order to prevent the telephone stand from slipping during this operation, the bottom thereof should be provided with any well known friction means.

Although a specific illustration of the invention 30 has been given, it will be understood that the principle herein disclosed can be carried out in numerous other ways than here disclosed.

Fundamentally, the invention involves an arrangement which permits the use of a reel for 35 electrical conductors carrying small currents, such as telephone currents, without a brake in the conductor thought necessary where a reeling operation is involved.

Applicant has illustrated several arrangements 40 for carrying out such a reeling operation but it will be obvious that other similar arrangements can be employed. Thus, for example, the principle of securing a portion of the conductor extending from the reel opposite to the end from 45 which the conductor is unreeled may be accomplished by securing this conductor to the center point of the hub, so that a minimum amount of movement of the wire occurs as the drum rotates. Moreover, although the invention has 50 been shown as applied specifically to telephone circuits, it can also be applied equally well to other types of circuits, some of which have been illustrated, such as in the operation of electric irons, vacuum cleaners and the like.

55 In the latter case, it may be advisable, due to the unusually long length of cord involved and also due to the larger size current values employed, to employ rotating brushes and rings.

It will accordingly be obvious that the invention 60 may take on other forms coming within the spirit of the invention herein disclosed and should not be restricted to the specific examples given but only as set forth in the appended claims.

We claim:

65 1. In a reel; a rotatable hub; a drum secured to and rotatable with said hub; a conductor wound on said drum; a first and second plate secured to and at one end of said hub and forming therebetween a chamber; said first plate having a radial slot extending from its periphery to said hub for admitting the conductor wound on the drum into said chamber; a removable casing for said reel; removable end covers for engaging said casing; an opening in said casing for providing a passage for said conductor from said

chamber to the exterior of said reel; and means for rotatably mounting said hub on said end covers.

2. In a reel; a rotatable hub; a drum secured to and rotatable with said hub; a conductor wound on said drum; a first and second plate secured to and at one end of said hub and forming therebetween a chamber; said first plate having a radial slot extending from its periphery to said hub for admitting the conductor wound on the drum into said chamber; a removable casing for said reel; removable end covers for engaging said casing; an opening in said casing for providing a passage for said conductor from said chamber to the exterior of said reel; and means for rotatably mounting said hub on said end covers, said means comprising a pin secured to said first end cover and protruding through said second end plate for pivoting said hub and a bearing secured to the other end cover for rotatably supporting said hub.

3. In a reel; a rotatable hub; a drum secured to and rotatable with said hub; a conductor wound on said drum; a first and second plate secured to and at one end of said hub and forming therebetween a chamber; said first plate having a radial slot extending from its periphery to said hub for admitting the conductor wound on the drum into said chamber; a removable casing for said reel; removable end covers for engaging said casing; an opening in said casing for providing a passage for said conductor from said chamber to the exterior of said reel; means for rotatably mounting said hub on said end covers, said means comprising a pin secured to said first end cover and protruding through said second end plate for pivoting said hub and a bearing secured to the other end cover for rotatably supporting said hub; and a spring, one end of which is secured to said last mentioned end cover and the other end is secured to said last mentioned plate, said spring being mounted within said hub.

4. In a reel; a rotatable hub; a drum secured to and rotatable with said hub; a conductor wound on said drum; a first and second plate secured to and at one end of said hub and forming therebetween a chamber; said first plate having a radial slot extending from its periphery to said hub for admitting the conductor wound on the drum into said chamber; a removable casing for said reel; removable end covers for engaging said casing; an opening in said casing for providing a passage for said conductor from said chamber to the exterior of said reel; means for rotatably mounting said hub on said end covers, said means comprising a pin secured to said first end cover and protruding through said second end plate for pivoting said hub and a bearing secured to the other end cover for rotatably supporting said hub; a spring, one end of which is secured to said last mentioned end cover and the other end is secured to said last mentioned plate, said spring being mounted within said hub; a ratchet formed in said bearing; and a pawl engaging said ratchet for locking said hub in any desired unreeled position.

5. In a reel; a rotatable hub; a drum secured to and rotatable with said hub; a conductor wound on said drum; a first and second plate secured to and at one end of said hub and forming therebetween a chamber; said first plate having a radial slot extending from its periphery to said hub for admitting the conductor wound on the drum into said chamber; a clamp for the conductor adjacent said hub for preventing slippage of the

conductor thereat; a removable casing for said reel; removable end covers for engaging said casing; an opening in said casing for providing a passage for said conductor from said chamber to the exterior of said reel; and means for rotatably mounting said hub on said end covers.

5 6. In a reel; a rotatable hub; a drum secured to and rotatable with said hub; a conductor wound on said drum; a first and second plate secured to and at one end of said hub and forming therebetween a chamber; said first plate having a radial slot extending from its periphery to said hub for admitting the conductor wound on the drum into said chamber; a removable casing 10 for said reel; removable end covers for engaging said casing; an opening in said casing for providing a passage for said conductor from said chamber to the exterior of said reel; a clamp at said opening for preventing slippage of said conductor 15 at said passage; and means for rotatably mounting said hub on said end covers.

7. In a reel; a rotatable hub; a drum secured to and rotatable with said hub and having a helical rib for guiding a conductor wound on said 20 drum; a first and second plate secured to said hub and forming therebetween a chamber; said first plate having a radial slot extending from its periphery to said hub for admitting the conductor wound on the drum into said chamber; a clamp 25 for the conductor adjacent said hub for preventing slippage of the conductor thereat; a removable casing for said reel; removable end covers for engaging said casing; an opening in said casing for providing a passage for said conductor 30 from said chamber; a clamp at said opening for preventing slippage of said conductor at said passage; a pivot comprising a pin protruding through said second end plate and secured to said first end cover for pivoting said hub and a bearing 35 secured to the end cover at the opposite end for rotatably supporting said hub; a spring mounted within said hub, one end of which is secured to said last mentioned end cover and the other end of which is secured to said second end plate; a 40 ratchet formed in said bearing and a cooperating pawl mounted in said drum for locking said reel in any desired position.

8. In a reel for telephones; a rotatable drum; 45 a first section of conductor wound on said drum; a second section of conductor extending through

said first section; a supporting means for said drum; means for rigidly clamping said supporting means in place on said telephone; spring means for holding said drum in a predetermined position; means for unreeling the conductor from said drum against the action of said spring means; said second section of conductor having its slack simultaneously taken up as said conductor is unreeled from said drum; said spring means acting upon release of the first section 10 of conductor to rewind said first section on said drum, said second section of conductor being simultaneously formed into a slack.

9. In a reel for telephones, a rotatable drum; 15 a first section of conductor wound on said drum; a second section of conductor formed in a loop, one end of said second section being clamped; a supporting means for said drum; means for rigidly clamping said supporting means in place on said telephone; spring means for holding said 20 drum in a predetermined position; means for unreeling the conductor from said drum against the action of said spring means; said second section of conductor having its slack simultaneously taken up as said conductor is unreeled from 25 said drum; said spring means acting upon release of said first section of conductor to rewind said first section on said drum; said second section of conductor being simultaneously formed 30 into a slack.

10. In a reel for telephones, a rotatable drum; 35 a first section of conductor wound on said drum; a second section of conductor formed in a loop, one end of said second section being clamped; a readily removable cover for said drum for permitting easy winding of the conductor on said drum; a supporting means for said drum; means for rigidly clamping said supporting means in place on said telephone; spring means for holding said drum in a predetermined position; means 40 for unreeling the conductor from said drum against the action of said spring means; said second section of conductor having its slack simultaneously taken up as said conductor is unreeled from said drum; said spring means acting upon release of said first section of conductor to rewind said first section on said drum; said second section of conductor being simultaneously 45 formed into a slack.
